UNITED STATES PATENT OFFICE.

COURTLAND MANNING, OF BRACKENRIDGE, PENNSYLVANIA, ASSIGNOR OF ONE-THIRD
TO MATTI LEHIKOINEN, OF BRACKENRIDGE, PENNSYLVANIA.

WRENCH.

No. 881,083.

Specification of Letters Patent. Patented March 3, 1908.

Application filed June 15, 1907. Serial No. 379,173.

To all whom it may concern:

Be it known that I, COURTLAND MANNING, citizen of the United States of America, residing at Brackenridge, in the county of Allegheny and State of Pennsylvania, have invented certain new and useful Improvements in Wrenches, of which the following is a specification, reference being had therein to the accompanying drawing.

10 This invention relates to wrenches, of that type commonly styled "monkey" wrenches.

The invention has for its object to provide a quick acting wrench wherein the use of screw threads and nuts is entirely eliminated 15 for adjusting the movable jaw of the wrench.

Another object of this invention is to provide a simple, inexpensive and durable wrench, that can be easily and quickly adjusted, the wrench being particularly designed for rotating nuts and similar objects having flat surfaces.

With the above and other objects in view which will more readily appear as the invention is better understood, the same consists 25 in the novel construction, combination and arrangement of parts to be presently described and then specifically pointed out in the appended claims.

Referring to the drawings forming a part 30 of this specification, Figure 1 is an elevation of a wrench illustrating the movable jaw thereof in section, Fig. 2 is a cross sectional view of a portion of the movable jaw taken on the line $x-x$ of Fig. 1, Fig. 3 is a horizontal sectional view of a wrench taken on the line $y-y$ of Fig. 1, Fig. 4 is a perspective view of the locking member of the wrench.

To put my invention into practice I construct my wrench of a shank 1 having a fixed 40 head or jaw 2. The shank upon its under edge is provided with teeth 3, and while the shank can serve functionally as a handle, I desire the privilege of placing the handle upon the shank if necessary.

45 Slidably mounted upon the shank 1 is a movable jaw 4, having straps 5' embracing the shank. The jaw 4 is provided near its upper end with a longitudinally disposed opening 5 having the side walls thereof provided with oppositely disposed grooves to constitute guide-ways 6. The opening 5 extends from one end of the jaw and is contracted at the other end, as at 7. Communicating with the opening 5 is a vertically disposed opening 8 for a headed pin 9 se-

cured in a locking member 10 slidably mounted in the opening 5. The locking member is provided upon its sides with ribs 11 adapted to fit in the guide-ways 6 of the jaw 4. The forward end of the locking member terminates in a tooth 12 adapted to extend from the contracted end 7 of the opening 5, while the rear end of the locking member 10 is bifurcated as at 14 and formed with a shank or pin 15. Surrounding the pin or shank 15 and within the opening 5 is a coil spring 16 confined within the opening under tension by a plate 17 suitably secured to the outer end of the jaw 4. The tension of the spring 16 is adapted to maintain the tooth 12 of the locking member in engagement with the teeth 3 of the shank 1, and when in such position, the tooth 12 is adapted to fit snugly in the contracted end of the opening 5. To release the locking member from engagement with the shank 1, the headed pin 9 is manipulated, said pin being moved towards the outer end of the jaw 4, withdrawing the locking member from engagement with the shank 1 and permitting of the jaw 4 being adjusted. The 70 jaw 4 can be quickly closed, as the beveled teeth 3 of the shank permit of the locking member residing over the shank while the jaw is being closed, but prevents such jaw from being opened, unless the locking member is manually moved out of engagement with the shank.

The wrench in its entirety is constructed of strong and durable metal, and the manner in which the operating parts of the wrench 80 are housed prevents the wrench from being injured by ordinary use.

Such changes in the details of construction as are permissible by the appended claims may be resorted to without departing 90 from the spirit and scope of the invention.

What I claim, and desire to secure by Letters Patent, is:—

A wrench comprising a toothed shank having a fixed jaw, the jaw slidably mounted 100 upon said shank, the upper portion of said slotted jaw provided with an opening having the inner end thereof contracted, the side walls of said opening formed with grooves to constitute guide ways, a locking member 105 arranged in said opening and provided with longitudinally extending ribs seated in said guide ways, said member having its forward end formed with a tooth adapted to extend through the contracted end of the opening 110

and engage with the teeth of the shank and said locking member having its other end bifurcated and carrying a pin approximately centrally of the opening formed by the bifurcation, a plate secured to the slideable jaw for closing the openings formed therein, a spring surrounding said pin and bearing against said locking member of the plate, said means having one end connected with

the shifting locking member and its other end 10 projecting from the jaw.

In testimony whereof I affix my signature in the presence of two witnesses.

COURTLAND MANNING.
